(57) **CLAIM**

The ornamental design for a remote control lever for UAV as shown and described.

DESCRIPTION

FIG. 1 is a front, right and top perspective view of a remote control lever for UAV, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an enlarged view of detail 8 in FIG. 1; and,
FIG. 9 is an enlarged view of detail 9 in FIG. 4.

The dashed broken lines depict portions of the remote control lever for UAV that form no part of the claimed design.

The dot-dash broken lines in FIGS. 1, 4, 8 and 9 depict the boundaries of the enlargements and form no part of the claimed design.
